UNITED STATES PATENT OFFICE.

ALBERT HOLBROOK, JR., OF PROVIDENCE, RHODE ISLAND, ASSIGNOR TO
JOHN B. WALSH, OF SAME PLACE.

MACHINE-BELTING.

SPECIFICATION forming part of Letters Patent No. 417,558, dated December 17, 1889.

Application filed September 20, 1889. Serial No. 324,529. (No specimens.)

To all whom it may concern:

Be it known that I, ALBERT HOLBROOK, Jr., of the city of Providence, in the county of Providence and State of Rhode Island, have 5 invented a new and useful Improvement in Machine-Belting, of which the following is a full, clear, and exact description, reference being had to the accompanying drawings, forming part of this specification.

10 This invention has reference to an improvement in the construction of round belting for conveying power; and it consists in the peculiar and novel construction of a round twisted belt of doubled and stitched woven fibrous material, as will be more fully set forth hereinafter.

15 The object of this invention is to produce a round twisted belt adapted for transmitting power, which, while pliable so as to bend 20 readily around a small pulley, will present a yielding exterior surface that will adjust itself to the groove in the pulleys, and will also possess greater strength than textile belting as heretofore constructed.

25 Figure 1 is a view of a doubled strip of woven textile material secured together by sewing and adapted to form a round belt by twisting the same. Fig. 2 is a sectional view of the strip shown in Fig. 1, showing the manner of folding the same and uniting the folded fabric by sewing. Fig. 3 is a view of the 30 twisted textile-fabric belting.

In the drawings, the number 4 indicates the strip of doubled textile fabric consisting of 35 canvas or other woven fabric adapted for use as belting.

55 represent the edges of the woven fabric, which fabric is first folded in the middle at 6. The so-folded fabric is now doubled at 40 one edge at 7, is folded around and over the

fold 6, so as to bring the edges 5 over the first fold at a point beyond the center of the folded strip, thus forming a strip consisting of six thicknesses of the woven fabric at one edge and extending over and beyond the center of the strip to the edges 5, beyond which the so-folded strip consists of four thicknesses of the woven fabric. The so-folded fabric is now sewed together along the center 8 with strong thread, so as to firmly hold the six 45 thicknesses together along the center of the strip. The strip shown in Figs. 1 and 2 is now twisted into the round belting shown in Fig. 3. The edge 7 of four thicknesses bends readily over the edges 5, which in the twisted 50 round belt form the inner core of the belting. The sewing unites all the layers firmly together. The strain on the belt is sustained 55 equally by all the six thicknesses of the fabric. This equalizing of the strain is materially facilitated by the peculiar manner of folding the woven fabric by which one edge is made of less thickness than the rest, so that in twisting the core or inner layers will not be upset and all the strain be exerted on the 60 outer layers or sheets of the folded material.

Having thus described my invention, I claim as new and desire to secure by Letters Patent—

A round belt consisting of a sheet of woven 70 textile material doubled and folded to bring the edges 5 beyond the center of the folded strip, one edge of the folded strip consisting of four and the opposite edge of six thicknesses sewed together along the central portion of the strip and twisted, as described.

ALBERT HOLBROOK, JR.
